UNITED STATES PATENT OFFICE.

JACOB RUSH SNYDER, OF PITTSBURGH, PENNSYLVANIA. ASSIGNOR TO PERCY E. DONNER, OF PITTSBURGH, PENNSYLVANIA.

STEAM-ENGINE REVERSING-GEAR.

1,252,190.

Specification of Letters Patent.

Patented Jan. 1, 1918.

Application filed August 15, 1916. Serial No. 115,074.

To all whom it may concern:

Be it known that I, JACOB RUSH SNYDER, a resident of Pittsburgh, in the county of Allegheny and State of Pennsylvania, have 5 invented a new and useful Improvement in Steam-Engine Reversing-Gears, of which the following is a specification.

This invention is an improvement in reversing gear mechanism for steam engines 10 and the like, and it relates more particularly to that type of such mechanism in which the means for moving the valve which controls the supply and exhaust of motive fluid to the reversing cylinder moves in a straight line.

15 One object of the present invention is to provide a mechanism of the character above described which can be applied to any type of locomotive.

A further object of the invention is to 20 provide an arrangement in which the valve setting means can be moved to the desired position without moving the usual oscillating bar connecting the valve moving means with the reach rod, or the reach rod itself, 25 thereby making it easy for the engineer to set the valve mechanism to the desired position.

A further object of the invention is to 30 provide mechanism of the character specified so arranged that the controlling valvular mechanism moves synchronously with the reach rod, and whereby, in the manipulation of the same, a substantially direct connection is formed between the operating 35 handle and the valve.

A further object of the invention is to 40 provide valve mechanism for devices of the kind specified so arranged that the exhaust from the reach rod locking cylinder is independent of the exhaust from the reversing cylinder, in order that the reach rod locking mechanism will not be liable to be intermittently applied by back pressure from the reversing cylinder.

45 Other objects and advantages of the invention will hereinafter appear.

The invention comprises the construction and arrangement of parts hereinafter described and claimed.

50 In the accompanying drawings, illustrating one embodiment of the invention, Figure 1 is in part a side elevation and in part a cross section of the mechanism, the view of the valve mechanism in the upper portion of the figure being taken on the line 1—1, Fig.

2, and the reversing cylinder being shown in longitudinal section; Fig. 2 is a plan view of the valve mechanism, its locking and its operating means; Fig. 3 is a transverse vertical section through the valve mechanism and its 60 operating means taken on the line 3—3, Fig. 2; Fig. 4 is a cross section of the reach rod locking mechanism on the line 4—4, Fig. 1; Fig. 5 is a plan view of the valve seat; Fig. 6 is a horizontal sectional view through the 65 rotary valve; and Figs. 7, 8, 9 and 10 are views of the valve seat in plan and the rotary valve in horizontal section showing various positions of the valve,—Fig. 7 showing the neutral position, Fig. 8 showing the 70 lock releasing position, Fig. 9 showing the same in position for applying pressure to one end of the reversing cylinder, and Fig. 10 showing the same in position to apply pressure to the opposite end of the reversing 75 cylinder.

The mechanism comprises a suitable fluid pressure motor 1 for operating the reach rod 2, a fluid pressure locking device 3 for locking said rod in different positions, valve 80 mechanism 4 for controlling the supply and exhaust of fluid pressure to and from the motor and locking device, and operating means 5 for the valve mechanism.

The fluid pressure motor shown comprises 85 a cylinder having a piston 6 therein connected by piston rod 7 to the cross head 8 to which the reversing rod 2 is attached, said reversing rod being connected to the usual link mechanism of the engine, not shown. 90 When the link mechanism is in neutral position, the piston 6 is stationed midway of the length of the cylinder, as shown in Fig. 1, and to drive the engine forwardly the reach rod is moved toward the right, viewing Fig. 95 1, by admitting fluid pressure to the left-hand end of the cylinder 1, and to reverse the engine the reversing rod 2 is moved toward the left, Fig. 1, by admitting fluid pressure into the right-hand end of cylinder 100 1.

The locking device 3 comprises a member 9 engaging one side of the piston rod 7, and a pivoted clamping member 10 for gripping the opposite side of said rod. The pivoted 105 member 10 is actuated to grip the rod by means of a movable abutment, such as the diaphragm 11, in a small power cylinder 12, said abutment carrying a projection 11^a contacting with the outer end of the member 110

10. Fluid pressure can be admitted to and exhausted from the cylinder 12 through pipe 13. When pressure is admitted into said cylinder, the movable abutment 11 actuates 5 the member 10 to grip the rod 7 and thus positively lock the latter in position. The means described is positively actuated to lock the rod to firmly hold it in position, but the locking means nevertheless is frictional, that is, the clamping members engage a smooth rod, and therefore permit the rod to be forcibly moved under abnormal conditions, without liability of breaking any of the parts as would be the case 15 with toothed and similar mechanical locks. This locking means will positively lock the rod 7 in any position of the latter, and does not require the rod to be in a certain position with a notch therein or a projection 20 thereon registering with complementary projections or notches on the locking means.

The valve mechanism for controlling the admission and release of motive fluid to and from the two ends of cylinder 1 and to 25 and from the locking cylinder 12, as shown, is of the rotary type, the same comprising a valve seat 14 with a coöperating rotary valve 15, the latter being maintained in engagement with the valve seat by means of 30 spring 16 and also by the fluid pressure admitted into the chamber underneath said valve through supply pipe 17, as shown in Fig. 3.

The valve seat, shown in detail in Fig. 35 5, is provided with four ports and one cavity or recess, as follows: A port 18 to which is connected the pipe 13 leading to the locking cylinder 12, a port 19 connected by means of pipe 20 to the right-hand end of cylinder 40 1, a port 21 connected by means of pipe 22 to the left-hand end of cylinder 1, a port 23 forming the exhaust for the pressure from the rod locking cylinder 12, and the recess or cavity 24 for supplying fluid pressure to 45 the locking cylinder 12 as hereinafter explained. Said valve seat is provided with a central bore 25 through which extends the stem 26 of the rotary valve 15, and which stem is hollow or provided with a central 50 opening 27 which forms the exhaust port for both ends of the cylinder 1. Each of the pipes 13, 20 and 22, as well as supply pipe 17, is provided with a section 28 of flexible tubing, of sufficient length to permit movement of the valve body 4, for a purpose hereinafter appearing, without destroying the fluid pressure connections.

The rotary valve 15, shown in detail in Fig. 6, has three arms or projections each 60 provided with cavities for coöperating with the ports in the valve seat. The arm 32 is provided with an irregular opening 33 arranged, in different positions, to coöperate with the ports 18 and 23 and cavity 24, for 65 controlling the admission and exhaust of

fluid pressure to and from the locking cylinder 12; the projection 34 is provided with a cavity 35 coöperating with the port 19 and communicating through port 36 with the central exhaust port 27, and thus controlling the admission and exhaust of fluid pressure to and from the right-hand end of cylinder 1. The projection 37 is provided with a similar recess 38 coöperating with the port 21 and communicating through the 70 port 39 with the central exhaust port 27, thus controlling the admission and exhaust of fluid pressure to and from the left-hand end of cylinder 1.

This valve has five functional or operative 80 positions as follows:

1. Neutral position, shown in Fig. 7. In this position cavities 35 and 38 register respectively with ports 19 and 21 and hence both ends of cylinder 1 are exhausted. The 85 lock exhaust port 23 is blank, cavity 33 uncovers port 18, and the projection 32 is in such position that the cavity 20 connects the supply chamber underneath the rotary valve with cavity 33. Consequently fluid 90 pressure is maintained in the locking cylinder 12. This is the normal running position.

2. Lock releasing position, shown in Fig. 8. This position is assumed by moving the 95 valve slightly counterclockwise from the position shown in Fig. 7. In this position the projection 32 has passed beyond the left-hand edge of cavity 20, thus stopping the admission of fluid pressure to the locking cylinder 12. At the same time the right-hand leg of projection 33 has slightly uncovered the lock exhaust port 23, thus allowing the locking cylinder 12 to exhaust, and unlocking the reach rod. The projections 100 35 and 38 have moved to disconnect ports 19 and 21 from exhaust port 27, but have not moved sufficiently far to uncover either of said ports 19 and 21 to the supply pressure. Consequently, both ends of the cylinder are 105 still without fluid pressure. This position is assumed upon the first movement of the rotary valve, so as to exhaust the locking cylinder slightly in advance of admitting pressure to either end of the cylinder.

3. This position is not illustrated, but is the same as that shown in Fig. 8. It occurs upon rotation of the valve 15 in the opposite direction, to wit, clockwise. All of the connections are as shown in Fig. 8, except that in this case the left-hand leg of cavity 33 has uncovered the lock exhaust port 23, while cavity 24 is entirely covered by the projection 32. In this position, as in that shown in Fig. 8, the locking cylinder 12 is 120 exhausted, but without admitting pressure to either end of the cylinder.

4. Engine reversing position, shown in Fig. 9. This position is reached from the position shown in Fig. 8 by a still further 125 130

movement of the rotary valve 15 in a counter-clockwise direction. In this position the locking port 18 is still connected by cavity 33 to lock exhaust port 23, thus maintaining the locking cylinder 12 exhausted. The cavity 38 still maintains connection between port 21 and exhaust port 27, the projection 35 has moved over sufficiently to uncover port 19, thus permitting supply pressure 10 from underneath the valve 15 to flow through said port 19 and pipe 20 to the right-hand end of cylinder 1, thus moving the piston 6, and with it the reach rod 2 toward the left, and moving the link mechanism in such direction as to reverse the engine.

5. Position for driving engine forwardly, shown in Fig. 10. This position is assumed from the third position, not shown, by a 20 still further movement of the valve in clockwise direction. In this position cavity 33 maintains the connection between lock port 18 and lock exhaust port 23, thus maintaining the locking cylinder exhausted. The 25 cavity 35 in projection 34 still maintains connection between port 19 and the exhaust port 27, but projection 38 has uncovered port 21, thus permitting supply pressure to flow from underneath the rotary valve 30 through said port 21 and pipe 22 to the left-hand end of cylinder 1, thus moving the piston 6 therein, and with it the reach rod 2, toward the right, and moving the link mechanism to such position as to cause the 35 engine to be driven forwardly.

It will thus be seen that in normal or running position both ends of the cylinder 1 are exhausted to the atmosphere, while the locking cylinder 12 is supplied with fluid 40 pressure to lock the reach rod into position to which it has been moved; that before fluid pressure is admitted to either end of the cylinder, the locking cylinder 12 is exhausted; that said locking cylinder remains 45 exhausted whenever fluid pressure is being admitted to either end of the cylinder 1; that when fluid pressure is admitted to one end of the cylinder, the opposite end of the cylinder is connected to the atmosphere; 50 and that the exhaust from the locking cylinder 12 is through a port 23, independent of the exhaust port 27 for the two ends of the reversing cylinder, as a result of which the lock can not be intermittently applied 55 by back pressure from the reversing cylinder.

The valve mechanism is supported by means of a stationary bracket 40 adapted to be mounted on the fire box or the side of a locomotive cab. The valve body 4 is 60 slidably mounted upon this bracket by being provided with a pair of projections 41 engaging in a groove or way 42 in bracket 40. Said valve body is caused to move with the reach rod 2, by being connected to the cross 65 head 8 by means of the reciprocating rod 43.

This bodily movement of the valve mechanism with the reach rod causes the valve mechanism to be automatically returned to neutral position when the reach rod reaches the end of its movement in either direction, 70 as will hereinafter appear.

The operating means for the valve mechanism comprises a handle 44 attached to a bar 45 also slidably mounted in the bracket 40, as shown clearly in Fig. 3. The handle 75 44 has a latch 46 provided with a toothed projection 47 which is normally held into engagement with a rack bar 48 on the stationary bracket 40, by means of the spring 49.

The lower face of sliding bar 45 is provided with a cam groove 50 with which operates a roller 51 carried by a reciprocating member 52 which latter is pivotally connected through member 53 to the crank arm 54 which is secured to the stem 26 of rotary valve 15. The cam slot 50 is offset, as shown in dotted lines in Fig. 2, so that when the sliding bar 45 is moved by means of handle 44, the cam roller 51 follows said slot 50 and causes the reciprocating member 52 to be 90 moved laterally or sidewise, and thus through connecting member 53, and arm 54 rotates the valve 15 in one direction or the other, depending upon which direction the handle 44 and sliding bar 45 are moved. It 95 will be observed that in normal position, Fig. 2, the roller 51 stands midway of the inclined portion of cam slot 50, so that no matter in which direction the sliding bar 45 is moved, rotation of the valve 15 is affected. 100

The parts are so arranged that to drive the engine forwardly, the handle 44 is moved forwardly, that is, to the right in Figs. 1 and 2, this movement rotating the valve 15 clockwise and permitting fluid pressure to 105 be admitted to the left-hand end of cylinder 1, whereas, to reverse the engine, the handle 44 is moved backwardly or to the left, thus rotating the valve 15 contra-clockwise and admitting fluid pressure to the right-hand 110 end of cylinder 1. When the handle has been moved to the desired position, it is locked in that position by the locking tooth 47. As the reversing rod moves, it carries with it bodily the entire valve mechanism, 115 and since the sliding bar 45 is now stationary, the cam roller 51 travels along the cam slot 50, and when it reaches the offset portion of said cam groove, the member 52 is moved laterally or sidewise, and through the 120 connecting member 53 and crank arm 54 automatically moves the valve 15 to neutral position, so that as soon as the reach rod has moved to the desired extent (determined by the position to which the handle 44 has been 125 set) the fluid pressure is immediately exhausted from the reversing cylinder, and pressure is admitted to the locking cylinder 12. Consequently, the mechanism requires no attention on the part of the engineer ex- 13

cept to move the handle 44 to the desired position, either forwardly or backwardly. All of the other operations take place automatically, without any manipulation at all 5 on the part of the engineer. During the time that fluid pressure is acting in the reversing cylinder, the lock is released, and at all other times the reach rod is positively locked in position, and atmospheric pressure 10 is maintained in the reversing cylinder.

No parts of the mechanism other than the sliding bar 45 are connected to the handle 44 and consequently the engineer can move this handle with the expenditure of very little 15 force, it not being required to move either the reciprocating rod 43 or the reach rod itself. Consequently the engineer need only to overcome the friction of the sliding bar 45 and of the rotary valve 15.

20 It will be understood that the structure shown is merely an illustration of one form of the mechanism, and that other structures may be devised which come within the spirit and scope of the appended claims.

25 What I claim is:—

1. In valve reversing mechanism, a fluid pressure motor for operating a reversing rod, fluid pressure locking means for locking said rod, valve mechanism for controlling 30 the supply of fluid to the motor and the locking means, means for operating the valve so that the locking means is unlocked and motive fluid is admitted to the motor to operate it, and connections between the valve 35 mechanism and the reversing rod for moving said mechanism bodily to thereby actuate it to exhaust the motive fluid from the motor and admit motive fluid to the locking means when the reversing rod has traveled 40 the desired extent.

2. In valve reversing mechanism, a fluid pressure motor for operating a reversing rod, fluid pressure locking means for locking said rod, valve mechanism for controlling 45 the supply of fluid to the motor and the locking means, and a slidable bar having camming connections with the valve mechanism for operating it to unlock the locking means and admit motive fluid to the motor, 50 said valve mechanism being slidably mounted and being connected to the reversing rod so that the valve mechanism is moved bodily with the reversing rod to cause the camming connections with the operating means to 55 turn the valve to neutral position as the reversing rod reaches the end of its movement to thereby exhaust the motive fluid from the motor and admit motive fluid to the locking means.

60 3. In valve reversing mechanism, a fluid pressure motor for operating a reversing rod, fluid pressure locking means for locking said rod, a rotary valve mechanism for controlling the supply of fluid to the motor 65 and the locking means, and a slidably

mounted bar having camming connections with the valve mechanism for operating it to unlock the locking means and admit motive fluid to the motor, said bar being manually operable and being provided with means 70 for normally locking it in stationary position, said valve mechanism being slidably mounted and being connected to the reversing rod so that the valve mechanism is moved bodily with the reversing rod to 75 cause the camming connections to actuate the valve to neutral position as the reversing rod reaches the end of its movement to thereby exhaust the motive fluid from the motor and admit motive fluid to the locking 80 means.

4. In valve reversing mechanism, a fluid pressure motor for operating a reversing rod, fluid pressure locking means for locking said rod, and valve mechanism for controlling 85 the supply of motive fluid to the motor and the locking means, said mechanism being slidably mounted in a stationary bracket adapted to be attached to an engine cab or fire box, a bar slidably mounted in 90 said bracket and provided with a handle having a latch for normally locking the bar in stationary position, said bar having a cam groove in the bottom thereof, and a cam roller coöperating with said groove, said 95 cam roller being carried by a reciprocating member connected to the valve for operating the same, so that as the slidable bar is moved the valve is actuated to unlock the locking means and admit motive fluid to the motor, and as the reversing rod is moved the valve mechanism is moved bodily so that the actuating means returns the valve to neutral 100 position as the reversing rod reaches the end of its movement to thereby exhaust the motive fluid from the motor and admit motive fluid to the locking means. 105

5. A power reverse gear for locomotives including a reversing rod, a fluid pressure motor for operating said rod, a fluid pressure-applied friction lock for locking the rod, valvular mechanism for controlling the motive fluid to and from the motor and to and from the locking means, and arranged 110 so that normally motive fluid is exhausted from the motor and admitted to the lock to keep it applied, means by which the valve may be manually operated to exhaust motive fluid from the lock and admit motive fluid to the motor to operate it, and connections 115 between the valvular mechanism and the reversing rod for moving the said mechanism bodily in synchronism with said rod to thereby actuate the valvular mechanism to exhaust motive fluid to the motor and admit motive fluid to the locking means when the reversing rod has traveled the desired extent. 120

6. A power reverse gear for locomotives including a reversing rod, a fluid pressure 125

motor for operating said rod, fluid pressure locking means for locking the rod, valvular mechanism for controlling the supply of motive fluid to and from the motor and the locking means and arranged so that normally motive fluid is exhausted from the motor and the lock applied, means for manually operating the valve to unlock the lock and admit motive fluid to the motor to operate it, and connections between the valvular mechanism and the reversing rod to move

said mechanism bodily to actuate it to exhaust the motive fluid from the motor and lock the rod when the reversing rod has traveled the desired extent. 15

In testimony whereof, I have hereunto set my hand.

JACOB RUSH SNYDER.
